United States Patent Office

Des. 229,681
Patented Dec. 25, 1973

229,681

ARCHITECTURAL UNIT

Mark L. Hildebrand, Altadena, Calif.
(157 Bowers Hill Road, Oxford, Conn. 06483)

Filed Sept. 1, 1971, Ser. No. 177,203

Term of patent 14 years

Int. Cl. D25—01

U.S. Cl. D13—1 J

Fig. 8.

FIG. 1 is a top view of my architectural unit.
FIG. 2 is a perspective view of my architectural unit.
FIGS. 3 and 4 are, respectively, the back and side views of the architectural unit of FIG. 2.
FIG. 5 is a cross-sectional view through 5—5 of FIG. 2.
FIGS. 6, 7 and 8 are, respectively, cross-sectional views through 6—6, 7—7 and 8—8 of FIG. 5.
FIG. 9 is a perspective view of my architectural unit.
I claim:
The ornamental design for an architectural unit, substantially as shown.
